UNITED STATES PATENT OFFICE.

EDMUND LICHTENSTEIN, OF BERLIN, GERMANY, ASSIGNOR TO DEUTSCHE MASCHINENBAU- UND VERTRIEBS-GESELLSCHAFT M. B. H., OF BERLIN, GERMANY, A FIRM.

DUPLICATING APPARATUS.

Application filed June 2, 1925, Serial No. 34,453, and in Germany July 21, 1924.

This invention relates to duplicating apparatus and more particularly to devices for tensioning flexible printing metallic foils on the impression cylinder of rotary printing machines.

Duplicators being at the present time simple marketable articles sold according to catalogue and operable by an operator in a simple manner, it may happen that the sheet of foil which has been provided with the written matter in a typewriter and which written matter is therefore visible on both sides of the sheet is stretched on the impression cylinder in a reverse manner that is to say with the surface prepared for printing placed downwardly by an unskilled operator. Efforts have been made to overcome this by perforating the sheets with unequally spaced holes.

It has been found however, that in rotary printing machines in which one end of the sheet is firmly secured to the impression cylinder and the other end of the sheet is resiliently attached to the impression cylinder the former end of the sheet is in operation worn more rapidly at the points of attachment than the latter end with the result that the sheet is rendered useless prematurely.

To obviate this disadvantage the unequally spaced holes are according to the present invention provided at both ends of the sheet and are arranged symmetrically in such a manner that while the sheet is prevented from being clamped in position with its wrong side up it is also capable of being turned through an angle of 180° about an axis at right angles to its plane for the purpose of interchanging the firmly and resiliently clamped ends before one of them is entirely worn out.

In order that the invention may be more easily understood and readily carried into effect reference may now be had to the accompanying drawings illustrating a preferred embodiment thereof and in which

Fig. 1 is a view of the tensioning roller of a duplicating machine.

Fig. 2 is a cross section of the impression cylinder of a duplicating machine and

Fig. 3 is a view of a sheet according to the invention.

The sheet *a* is drawn tightly about the surface of the cylinder *c* as shown in Figure 2 and has one of its ends attached thereto by

pins *b*. The other end of the sheet is attached by pins *d* to the tensioning roller *f* which is under the action of a spring *g* and is adapted to cause the sheet to closely embrace the periphery of the cylinder.

The perforations of the sheet are preferably such, that the distance between consecutive holes *h* is different. As shown in Figure 3 it will be noted that the holes in the top end of the sheet are such that starting from the left the distance between them continually increases. At the bottom end the arrangement is exactly the reverse. With this form of connection it is quite impossible to place the sheet on the pins with the wrong face uppermost.

As shown in the drawing the unequally spaced perforations at the two ends of the sheet are arranged symmetrically according to the invention, in such a manner that while the sheet is prevented from being placed on the impression cylinder with the wrong face uppermost it is capable of being turned through 180° about an axis at right angles to its plane so as to reverse the ends of the sheet, and therefore it is possible to turn the sheet through 180° in the plane thereof about an axis at right angles to this plane. This is particularly important where the sheet is clamped rigidly at one end and resiliently at the other end, but is also of advantage for the many other methods of attachment in use.

The metal foil being an exceedingly delicate membrane is ordinarily but feebly resistant to the strains to which it is subjected incidental to its application to the cylinder of the duplicator and to its subsequent use in printing, so that when fastened on the studs in the usual manner by one or two holes, it is soon torn off. But, in the present instance, in which a plurality of transversely distributed holes are used cooperating with a like member of studs on the duplicator, the stencils are substantially uniformly distributed over the walls of all the holes on one end of the foil sheet so that the sheet is not overstressed at any one point, the life of the sheet being thereby prolonged.

For particular constructions of duplicating machines the perforation intervals could also be chosen variably so as to prevent unsuitable sheets from being used in the machine.

What I claim is:—

1. Duplicating apparatus comprising, an impression cylinder, a tension roller operatively associated therewith, a row of pins on the impression cylinder, a row of pins on the tension roller, the distances between successive pins in each row increasing in the same ratio but from opposite sides of the sheet. 10
5 ratus, the sheet having a row of holes at one end and a row of holes at the other end, the distances between consecutive holes in each row increasing in the same ratio but from opposite sides of the sheet. In testimony whereof I have signed my 15 name to this specification.

2. A sheet for use in duplicating appa-
